UNITED STATES PATENT OFFICE

97,957

DESIGN FOR A TEMPLE MEMBER FOR SPECTACLES OR SIMILAR ARTICLES

Edwin Reynolds, Vineland, N. J.

Application August 31, 1935, Serial No. 58,382

Term of patent 14 years

To all whom it may concern:

Be it known that I, Edwin Reynolds, a citizen of the United States, residing at Vineland, in the county of Cumberland and State of New Jersey, have invented a new, original, and ornamental Design for a Temple Member for Spectacles or Similar Articles, of which the following is a specification, reference being had to the accompanying drawing, forming part thereof, in which:

Figure 1 is a top perspective view of a temple member for spectacles or similar articles showing my new design; a dominant feature of which is the inwardly extending pad;

Figure 2 is a bottom perspective view; and
Fig. 3 is a bottom plan view of the same.

The temple member as shown on the drawing is on an enlarged scale.

I claim:

The ornamental design for a temple member for spectacles or similar articles, substantially as shown and described.

EDWIN REYNOLDS.
